UNITED STATES PATENT OFFICE.

OTTO HOLSTEIN, OF ST. PAUL, MINNESOTA.

DEVICE FOR CLEANING FUR ARTICLES.

Application filed June 14, 1922. Serial No. 568,118.

To all whom it may concern:

Be it known that I, OTTO HOLSTEIN, a citizen of the United States, residing at St. Paul, in the county of Ramsey and State of Minnesota, have invented certain new and useful Improvements in Devices for Cleaning Fur Articles, of which the following is a specification.

This invention relates to devices for cleaning fur articles, and more particularly to that class of devices designed for cleaning fur garments, an object of the invention being the provision of a portable power driven cleaning instrumentality which may be conveniently and easily moved over a dressed pelt or garment without injury to the hairy coating or the many seams ordinarily joining the numerous skins of which a garment is made.

A further object of the invention is the provision of enclosed rotary cleaning mechanism to be used in connection with a cleaning medium such as prepared sawdust and the like, whereby the cleaning medium is controlled to move in a cycle to thereby be repeatedly brought into contact with the fur to effect a continuous cleaning operation as the device is moved over the surface.

Ordinarily, fur articles are cleaned by the use of a prepared medium such as sawdust, which is vigorously rubbed into the hairy coating by hand, the sawdust having been previously prepared to render it capable of scouring the hide and pick up the dust particles from the hairy coating. In order to thoroughly cleanse the fur in this manner without injuring it, it is essential that the medium be rubbed vigorously into the same and at the same time exercise care with regard to the seams of the various skins so that the abrasion will not rend the threads of the seams. This process, obviously, is very slow and tedious and results in uneven cleaning, inasmuch as it is impossible to rub all parts of the skin uniformly.

Further, in the hand process the sawdust is flipped about by the hairy coating thus rendering it difficult to mass the cleaning medium and concentrate it on a single spot.

I provide a device which may be selectively moved over the surface to any part of the garment and is entirely enclosed to prevent scattering of the cleaning medium, which is capable of controlling the latter to apply

a given volume thereof over and over again to the hairy coating.

It is also an object of the invention to provide as a part of said cleaning mechanism, means whereby the cleaning medium is uniformly and continuously brought into frictional cleaning contact with the hide and its hairy coating under a constant uniform pressure so that all parts of the fur will be subjected to precisely the same cleaning operation, as distinguished from the uneven hand cleaning process.

A further object of the invention is to provide in connection with said mechanism, means whereby, when the cleaning process is completed, the cleaning medium may be extracted from the hairy coating and collected.

A present method of removing the cleaning medium from the fur, consists in subjecting the fur to a beating as by straps of leather or the like, to loosen the particles held captive in the hairy coating, the beating usually taking place in a current of air which is depended upon to carry off the loosened particles as they bound into the air during the beating process. This, also, is a tedious, slow and inefficient process involving a subsequent vigorous shaking and brushing. By including in the mechanism this feature of extracting and collecting the cleaning medium, I obviate great expense over present methods, secure better results with practically no injury to the hairy coating, as distinguished from the injurious strapping process described above.

Other objects of the invention will be pointed out as this specification progresses, the invention consisting in the construction combination and arrangement of parts hereinafter described and specifically claimed.

In the accompanying drawings forming part of this specification:

Figure 1, represents a perspective view of one form of my improved fur cleaning device.

Fig. 2, is a perspective view of the device showing it upside down.

Fig. 3, is a vertical sectional view on line 3—3 of Fig. 1.

Fig. 4, is a sectional view on line 4—4 of Fig. 1.

Fig. 5, is an enlarged sectional view on line 5—5 of Fig. 1.

Fig. 6, is a perspective view of one of the movable journal blocks for the rotary element of the device.

Fig. 7, is a diagrammatic side view of the body of the rotary element.

Fig. 8, is a diagram illustrating the method of forcing the cleaning medium into the hairy coating, and

Fig. 9, is a fragmentary view of a detail.

In the drawings, I have illustrated a preferred form of my invention, which is especially adapted for use in cleaning fur having a fine soft hairy coating grown thick on the skin, or for rugs, and the like, and which is provided with a motor adapted to be driven from a source of electric current such as an ordinary lamp socket.

In the drawings 1 designates a somewhat elongated outer casing having parallel end walls 2, an outwardly inclined front wall 3, a preferably semi-circular rear wall 4, and a flat top wall 5. The top wall is formed with a longitudinally disposed hinge 6 extending parallel with the front wall and spaced forward of the longitudinal center of the casing, whereby is formed the hinge cover or door 5', the latter having a down-turned lip 5''. By means of this door access is obtained to the interior of the casing.

The casing is open at its bottom, the opening being defined by the lower edges of the front and rear walls 3 and 4 respectively, said casing being formed with a pair of partition walls 7 and 8, which are parallel with the end walls 2 and spaced respectively, a relatively small distance therefrom to form wheel chambers 9, and a central relatively large brush chamber 10. In the walls 3 and 4, spaced along the lower edges thereof, respectively, are the openings 10', which are in lateral alignment relative to the casing and adapted to receive the hooks 11 of the grate 12, said grate being here shown as consisting of side bars 13 and transverse bars 13' extending between said side bars. The transverse bars are preferably curved outwardly and may be sprung into straight contour to cause the hooks 11 to disengage the front and rear walls when it is desired to remove the grate from the casing. The grate functions to prevent the pelt from wrinkling in the process of cleaning.

Rotatably supported by the end walls 2 of the casing so as to rotate in a plane parallel with the former and be located approximately concentric with the semi-circular rear wall 4 of the casing, is the rotary element or cylindrical bristle brush 14, said brush consisting of a central arbor or shaft 15, and a cylindrical body portion 16 carrying tufts of bristles 16' of uniform length to form a true cylindrical brush, as is best indicated in Figure 2. The tufts of bristles are preferably distributed over the cylindrical body portion 16, in the form of op-

posed helices directed from a median line on said body portion outwardly and forwardly in the direction of rotation of said body portion, as indicated by the arrow in Figure 7, for a purpose hereinafter to be explained.

In Figures 1 and 2 of the drawings, but one row of bristle tufts is shown, but it is to be understood that any chosen number of rows may be utilized as desired.

The rotary element is mounted in the end walls in the following manner:

Referring to Figure 9 of the drawings, the end walls are cut away to form downwardly opening journal receiving slideways 17, which extend preferably at right angles to the respective lower edges of the end walls. Fitting slidably into these slideways, one for each end wall, is the journal block 18 formed with parallel grooves 19 adapted to slidably receive the side edges of the slide-way 17. The journal block is further provided with bolt holes 18' adapted to receive bolts 18'', which latter are threaded into the openings 18''' in the respective end walls.

The journal block is further formed with the journal 19', wherein is journaled the shaft 15 as shown in Figure 3. Rotatably mounted on said shaft, one for each of the wheel chambers, are the supporting wheels 20, the peripheries thereof extending slightly through the open bottom of the casing and slightly beyond the grate bars 13', as is best shown in Figure 3.

The diameter of the cylindrical brush is preferably approximately equal to the diameter of the supporting wheels, which latter are adapted to roll over the dressed pelt or fur garment *a* as indicated in Figure 4, the garment being laid out on the flat surface of the work table *a'*. The lower edge 4' of the rear wall is so located relative to the brush as to approximately just contact with the bristles thereof or be brushed thereby while the lower edge 3' of the front wall is spaced an appreciable distance outwardly from the periphery of the brush to form a gap *b* therebetween.

The partition walls 7 and 8 are likewise cut away as at 21, to permit the rotary brush to be removed from the casing when the screws 18'' of the journal box have been removed.

Rigid on the shaft 15 outside of the end wall 2 adjacent the partition wall 8, is the driven pulley 22, having belt connection 23 with a driving pulley 24 of the electric motor 25, the latter being preferably secured to the top of the casing and having its driving shaft 26 arranged parallel to the shaft 15. Conductor wires 27 are provided, whereby the motor may be connected with a source of electric current such as an ordinary electric light socket (not shown). A suitable switch 27' connected into the line serves to stop and start the device as de-

sired. Thus, when the motor is actuated, the brush will rotate in the direction indicated by the arrow in Figure 4.

In operation a quantity of cleaning medium such as the sawdust *c* is placed upon the dressed pelt or garment and the device manipulated (as by means of the handle 28 provided for that purpose) to slowly traverse the pelt in engagement with the cleaning medium, the device being slightly tilted rearwardly on the heel formed by the curved rear wall adjacent the edge 4' as indicated in Figure 4, to thereby raise the lower edge 3' of the front wall to bring the sawdust into engagement with the rapidly rotating brush. As the bristles approach the hairy covering and engage with it in their journey to the lower edge 4' of the rear wall, the sawdust is vigorously brushed into commingling relation with the hairy covering of the pelt as is best indicated in Figure 8. As the tuft passes the lower center of revolution, it will brush the sawdust past the edge 4' and into the semi-circular end 25 of the casing as indicated in Figure 4. Thus, the rotating brush will carry the sawdust peripherally through the interior of the casing and deposit it on the inside of the inclined front wall 3 as is best indicated in Figure 5, when the sawdust will descend through the gap *b* into the path of the brush, and the process will be repeated. Thus, a definite quantity of cleaning medium may be whirled through a cycle or 35 circuit within the casing as the machine is caused to traverse the pelt from place to place.

As the bristle tufts are of uniform size and flexibility, the cleaning medium is brought into engagement with the hairy covering at a constant uniform pressure, thus effecting an even cleaning operation in all parts of the pelt. After the pelt is thoroughly cleansed it is desirable that the cleaning medium be removed from the hairy covering. To accomplish this, with the same cleaning instrumentality, I have provided the collapsible shelf 29, extending swingably between the partition walls 7 and 8, 45 and having pivotal support 29' at its opposite ends in the walls 7 and 8, respectively. The free edge 30 of the shelf, when swung upwardly past the vertical as indicated in Figure 5, is on a level with the upper edge 50 of the front wall 3, so that when the door or cover 5' is closed the shelf is restricted in its inward swinging movement. When it is desired to collect the cleaning medium, the shelf is swung rearwardly as indicated in Figure 4 to bring its free end 30 into peripheral contact with or close proximity to the rotating brush 14. Thus, the sawdust is deposited onto the top of the shelf. The shelf is supported at each end by means of 55 a set of pivotally connected links 31 and 32,

the former being pivotally connected by means of the pivot 33 to the respective partition walls and the latter by means of the pivot 34 to the opposite end of the shelf. The connected links may be bent upwardly 70 and the shelf swung into the position shown in Figure 5. To protect the running parts of the device a suitable guard plate 35 is provided, the latter being secured as by means of screws 35 to the casing. 75

By arranging the bristle tufts as described, the cleaning medium is swept centerward, and the sweeping or cleaning action is continuous inasmuch as the rear bristle tufts of an advance row, still engage the fur when the forward bristles of the next following row come into action. If the bristle tufts were arranged in lines parallel with the shaft 15, longitudinal gaps between the bristles would be formed, which would cause 85 all the tufts to strike the hairy covering at one time and tend to pull the hair and wrinkle the pelt.

I have found that a liberal sized gap between helical rows operates very satisfactory without injuring the fur. 90

While I have shown supporting wheels to facilitate manipulation of the device, it is to be understood that these are not absolutely essential as the casing may be slid 95 on its underside and suitably tilted by pivoting it on its heel.

I claim:

1. A device for cleaning fur articles comprising a casing adapted to be readily moved over the hairy covering of a fur article, said casing including a front and rear wall extending downwardly and inwardly to define an opening between their respective lower edges, and a power driven brush mechanism including a cylindrical bristle brush rotatably mounted in said casing in a manner to extend through said opening and be spaced from the lower edge of said front wall and to peripherally engage when said mechanism is actuated the hairy covering of the fur article and brush over the lower edge of said rear wall for the purpose set forth. 100

2. A device for cleaning fur articles, comprising a casing adapted to be slid over the hairy covering of a fur article, said casing including a front and rear wall so disposed as to define an opening between their respective lower edges, a power driven cylindrical bristle brush rotatably mounted in the casing, the axis of rotation thereof being disposed parallel with the sides of said opening and the bristles thereof extending through said opening, into brushing engagement with the lower edge of said rear wall and the hairy covering of the fur article, when said brush is actuated and the casing is slid. 115

3. A device for cleaning fur articles com- 120

prising a closed casing formed with an elongated opening of uniform width in its underside, said casing being adapted to be readily moved over the hairy covering of the fur article, and a power driven brush rotatably mounted to rotate within the casing and extend with its periphery through said opening into brushing contact with the fur article, said brush being bodily positioned relative to said opening to completely obstruct the latter except for a relatively narrow space immediately adjacent one long side thereof.

4. A device for cleaning fur articles with a granular cleaning medium comprising a closed casing formed with an elongated opening of uniform width in its underside, said casing being adapted to be moved over the hairy covering of the fur article and the cleaning medium applied thereto, and a rotary brush having connection with driving means to be driven thereby, rotatably mounted to rotate within the casing and extend sidewise in spaced relation relative to one long side of said opening through the latter into brushing contact with the fur article for the purpose set forth.

5. In a device for cleaning fur articles comprising, in combination, a closed casing formed with an elongated opening in its underside, said casing being adapted to be bodily manipulated to traverse the hairy covering of a pelt, and a rotary brush having connection with driving means to be driven thereby rotatably mounted to rotate within the casing and extend through said opening to brush the pelt when the brush is actuated, said casing including a wall arranged parallel to said brush, at one side thereof, and spaced therefrom to form a gap therebetween in open communication with said opening, and a wall opposite the aforesaid wall and parallel therewith located on the other side of said brush and spaced therefrom and extending with its lower edge into contact with the periphery thereof.

6. In a device for cleaning fur articles, with a cleaning medium such as sawdust, comprising in combination, a closed casing formed with an elongated opening in its underside, said casing being adapted to be bodily manipulated to traverse the hairy covering of a pelt, previously sprinkled with a cleaning medium, and power driven brushing means including a motor adapted to be connected with a source of power and a rotary brush mounted to rotate within the casing and extend through said opening to brush the cleaning medium into the pelt when the brush is actuated, the surrounding walls of said casing including a wall located in front of said brush and spaced therefrom to form a space between in open communication with said opening, and a wall located behind said brush in parallelism therewith

and spaced therefrom to conform to the periphery thereof, and have its lower edge sufficiently close to the brush to catch particles of cleaning material brushed from the pelt for the purpose set forth.

7. In a device for cleaning fur articles, with a cleaning medium such as sawdust, comprising in combination, a closed casing formed with an elongated opening in its underside, said casing being adapted to be readily slid over the hairy covering of a pelt previously sprinkled with a cleaning medium, and a rotary brush adapted to be driven from a source of power to be rotated thereby, mounted to rotate within the casing and extend through said opening to brush cleaning medium against the pelt when the brush is actuated, said brush being positioned to brush over one of the long edges of the casing forming the sides of said opening, and spaced grate bars extending across said opening for the purpose set forth.

8. In a device for cleaning fur articles by the use of a granular cleaning medium, comprising in combination, a casing formed with an opening in its underside adapted to be propelled over the hairy covering of the pelt, a rotary bristle brush mounted over said opening, to rotate within the casing and extend with its bristly periphery into brushing contact with the hairy covering of the pelt and with one of the edges of the casing bordering on said opening, means for rotating said brush in the direction of said brush engaging edge, and a formation in the casing structure whereby an area is formed within the casing, which area is in open communication with said opening and is traversed by the downwardly moving bristles of said brush when the latter is actuated, and is adapted to hold a supply of the cleaning medium in a manner to cause it to fall during a cleaning operation into the path of the moving bristles to be thereby carried in a continuous stream into frictional engagement with the hairy covering of the pelt concurrently with a sliding movement of the casing.

9. A machine for rubbing a granular cleaning medium such as sawdust into the hairy covering of a pelt, comprising in part an open bottom casing adapted to be propelled over the hairy covering of the pelt upon which a granular cleaning material has been previously deposited, a power driven cylindrical rotary brush rotatably mounted in the casing, the periphery of the brush extending through the open bottom of the casing into the depth of said hairy covering to apply, when the brush is actuated, a continuous uniform wiping pressure against said cleaning material to force it into frictional engagement with the individual hairs of the hairy covering.

10. A machine for brushing a quantity of

- granular cleaning medium such as sawdust in a continuous stream into commingling relation with the hairy covering of a pelt to cleanse it, comprising in part, a casing which is adapted to be moved over the hairy covering, an opening in the underside of the casing through which the hairy covering projects and upon which latter the cleaning medium is placed, a power driven cylindrical brush, rotatably mounted in the casing in such a manner as to brush the cleaning medium into commingling relation with the hairy covering when the brush is actuated, said brush being located relative to the edges of said opening to cause the cleaning medium to be swept from said commingling relation into the interior of the casing in the direction of rotation of the brush and carried by the latter over the top thereof onto the pelt to be again brought into commingling relation with the pelt as before.
11. The combination with a device as set forth in claim 10, of a shelf in front of the brush extending from the wall of the casing to the periphery of the brush to catch the cleaning medium carried over by the latter when the brush is actuated, and connecting means between said shelf and casing to enable said shelf to be folded against the wall of said casing.
12. In a device for brushing a granular cleaning medium into the hairy covering of a pelt to cleanse it, the combination, with a casing formed with an opening in its underside, said casing being adapted to be propelled over the hairy covering and the cleaning medium deposited thereon, a rotary brush mounted in a manner relative to said opening to extend through the latter and initially brush cleaning medium into commingling relation with the hair of the pelt and finally out of same and into said casing and carry it over the top of the brush back to the pelt, to be again brushed into the hairy covering as before when the brush is actuated to thereby effect a continuous circuitous movement of the cleaning medium, and means for rotating said brush; of a pair of supporting wheels for supporting said brush in proper operative position relative to the pelt one for each end of the brush, said wheels being rotatably supported on said casing to rotate about the axis of rotation of said brush.
13. In a device for brushing a granular cleaning medium into the hairy covering of a pelt to cleanse it, the combination with a casing formed with an opening in its underside, said casing being adapted to be propelled over the hairy covering and the cleaning medium deposited thereon, a rotary brush mounted in a manner relative to said opening to extend through the latter and initially brush cleaning medium into commingling relation with the hair of a pelt and finally out of same and into said casing and carry it over the top of the brush back to the pelt, to be again brushed into the hairy covering as before, when the brush is actuated, to thereby effect a continuous circuitous movement of the cleaning medium and means for rotating said brush; of means within the casing located in front of said brush in the path of the circulating cleaning medium for intercepting and holding the latter, said means including an inclined plate hingedly mounted on the casing to enable the plate to be swung out of the path of the cleaning medium.
14. In a device for brushing a granular cleaning medium into the hairy covering of a pelt to cleanse it, the combination with a casing formed with an opening in its underside, said casing being adapted to be propelled over the hairy covering and the cleaning medium deposited thereon, a rotary brush mounted in a manner relative to said opening to extend through the latter and initially brush cleaning medium into commingling relation with the hair of a pelt and finally out of same and into said casing and carry it over the top of the brush back to the pelt, to be again brushed into the hairy covering as before, when the brush is actuated, to thereby effect a continuous circuitous movement of the cleaning medium and means for rotating said brush; of means within the casing forward of said brush adapted to be extended into the path of said circulating cleaning medium for intercepting and holding the latter, and an opening fitted within a closure, in the wall of the casing to gain access to said means.
15. In a device for brushing a granular cleaning medium into the hairy covering of a pelt to cleanse it, the combination of a casing formed with an opening in its underside, said casing being adapted to be propelled over the hairy covering and the cleaning medium deposited thereon, a rotary brush rotatably mounted in a manner relative to said opening to extend through the latter and initially brush cleaning medium into commingling relation with the hair of the pelt and finally out of same and into said casing and carry it over the top of the brush back to the pelt, to be again brushed into the hairy covering as before, when the brush is actuated, to thereby effect a continuous circuitous movement of the cleaning medium and means for rotating said brush; and a handle for the casing whereby the latter may be propelled over the pelt and tilted rearwardly to raise the front thereof over piles of cleaning material to bring the latter into operative relation with the brush.
16. In a device for brushing a granular cleaning medium into the hairy covering of a pelt to cleanse it, the combination of a cas-

6
ing formed with an opening in its underside, said casing being adapted to be propelled over the hairy covering and the cleaning medium deposited thereon, a rotary brush 5 mounted in a manner relative to said opening to extend through the latter and initially brush cleaning medium into commingling relation with the hair of the pelt and finally out of same and into said casing and carry it 10 over the top of the brush back to the pelt, to be again brushed into the hairy covering as before, when the brush is actuated, to

thereby effect a continuous circuitous movement of the cleaning medium and means for rotating said brush, said brush consisting 15 in part of an elongated body member, and spaced rows of radial bristle tufts extending longitudinally of said body member on the periphery thereof, each row being crooked to a degree intermediate its ends to 20 cause one row to overlap the adjacent row for the purpose set forth.

In testimony whereof I affix my signature.
OTTO HOLSTEIN.
